UNITED STATES PATENT OFFICE.

CHARLES A. CURRAN, OF ALBANY, OREGON.

FRUIT-DRIER.

SPECIFICATION forming part of Letters Patent No. 272,590, dated June 5, 1883.

Application filed February 8, 1883. (No model.)

To all whom it may concern:

Be it known that I, CHARLES A. CURRAN, of Albany, in the county of Linn and State of Oregon, have invented certain new and useful 5 Improvements in Fruit-Driers; and I do hereby declare that the following is a full, clear, and exact description thereof, reference being had to the accompanying drawings, and to the letters of reference marked thereon, which 10 form part of this specification, in which—

Figure 1 is a vertical section taken horizontally through the center of my improved fruit-drier, showing the trays arranged therein. Fig. 2 is a transverse section taken vertically 15 through Fig. 3, the casing and trays being omitted for the purpose of clearly exposing to view the radiating pipe on one side thereof; Fig. 3 is a side elevation without the casing; Fig. 4 is a perspective view of one of my 20 proved trays for supporting the fruit-pans.

This invention relates to novel improvements on fruit-driers, which will be fully understood from the following description, when taken in connection with the annexed drawings.

25 A A designate the outer walls, which form the base of the drier and inclose two furnaces, B B, which are surrounded by a hot-air space, and which are prismatic in cross-section, their side walls forming angles and inclined planes, 30 p p', as shown in Fig. 2, for the purpose of allowing the use of inclined shielding-walls, hereinafter described.

The furnaces B B are provided with end doors, and, if desired, grates may be arranged 35 in them. From the inner ends of the furnaces rise pipes C C, to which are attached a series of horizontal coils, C', of pipes, as shown in the drawings, which coils, together with the furnace-walls, afford a very large amount of 40 heat-radiating surface in a comparatively small space.

By constructing the coils of pipes as shown and arranging them horizontally, the heated products of combustion are compelled to take 45 a very tortuous course through the drying-chamber P, which is inclosed by walls P', having end doors, P², all of which are above the walls A. One of the trays I have represented in Fig. 4, and it will be hereinafter described.

E E designate inclined walls, which extend 50 from one end of the hot-air space to the other on opposite sides of the furnaces B B. These walls are opposite the lower cold-air draft-openings, a a, through the side walls, A A, and between these latter walls and the walls E E 55 are spaces in which the cold air is first received on entering the drier. It will be seen that the walls E E serve as shields and prevent cold-air currents from impinging against the furnace-walls B B.

Above the level of the top plates of the furnaces I make draft-openings b, for tempering or regulating the heat of the drier, and these 60 openings, as well as the openings a a, are provided with sliding dampers for regulating the 65 quantity of air admitted into the drier. I am by these means able to thoroughly and uniformly ventilate the drier and to subject the fruit therein to currents of dry air, which will rapidly carry off the moisture.

The trays which I use in the upper part of my drier I construct as follows:

G designates a rectangular frame, across the middle of the length of which is a brace-bar, G'. At the corners of the frame G, inside 75 thereof, are angular staples e, to which the ends of angular braces H H are connected by eyes. The angles of these braces are connected by rings to loops g, which are rigidly secured to buckle-plates J J, through which a screw, 80 K, is tapped, having short thumb-pins projecting from it.

It will be seen that by a single adjustment of the screw K the frame G can be tightened.

These trays, which are designed for supporting the fruit-pans, may be sustained by means of grooves in the side walls of the casing P, or in any other suitable manner.

Having described my invention, what I claim as new, and desire to secure by Letters Patent, 90 is—

1. In a drying-furnace, the combination of the external rectangular furnace-walls, A, the cold-air-inlet passages a, near the bottom of these walls, provided with sliding dampers, 95 furnaces B, having inclined side walls and outlets C', and the inclined shields E, arranged in the angular spaces between the furnaces and

the outer walls, A, all constructed and adapted to operate substantially in the manner and for the purposes described.

2. A fruit-tray frame consisting of the frame 5 G, braced by rod G', in combination with corner-staples e, braces H, and a turn-buckle connecting these braces, all constructed and adapted to operate substantially in the manner and for the purposes described.

In testimony that I claim the foregoing as 10 my own I affix my signature in presence of two witnesses.

CHARLES A. CURRAN.

Witnesses:

J. A. DAVIS,
J. K. WEATHERFORD.
